(57) **CLAIM**

The ornamental design for an illuminated sign, as shown and described.

DESCRIPTION

FIG. 1 is a front perspective view of an illuminated sign showing my new design;

FIG. 2 is a rear perspective view thereof;

FIG. 3 is a front elevation view thereof, the back elevation view being the same;

FIG. 4 is a right side elevation view thereof, the left side elevation view being the same;

FIG. 5 is a top view thereof; and,

FIG. 6 is a bottom view thereof.

The broken lines depict portions of the article and form no part of the claimed design.
